Chas. Silver

Attorney

Patented Sept. 27, 1927.

UNITED STATES PATENT OFFICE.

HAROLD S. BENNETT, OF BALTIMORE, MARYLAND.

SELF-SOAPING MOP.

Application filed April 2, 1927. Serial No. 180,436.

This invention relates to improvements in self-soaping mops and has particular reference to a mop possessing novel advantages for washing and cleaning dishes and similar receptacles.

Among the objects of this invention is to provide a mop having a perforated container for holding a supply of soap or other suitable detergent, said container being of a pliable material, such as rubber.

Other, further and more specific objects of this invention will become readily apparent to persons skilled in the art from a consideration from the following description when taken in conjunction with the drawings wherein:

Fig. 1 is a side view of the mop, a portion of the device being broken away to show the relative positions of the handle, perforated soap container and mop yarn.

Fig. 2 shows a suitable perforated container for my device to hold the soap or other suitable detergent.

The apparatus comprises the handle (1) upon which is securely bound the mop yarn (2) by means of a cord (3) which may be made of the same material as the mop yarn (2). As an aid in securing the mop yarn to the handle (1), a peripheral groove (4) is provided near one end of the handle. At this end of the handle (1), a bead or other suitable peripheral projection (5) is provided, which serves to support and hold the perforated container (6) upon the handle (1). This container (6) is of a resilient pliable material, such as molded rubber, and although I prefer the spherical construction disclosed in the drawing, it is to be understood that other suitable shapes may be used

without departing from the spirit and scope of this invention. In fitting the container (6) to the mop, the neck (7) is slipped over the bead (5), from which it may be readily detached by a slight pull. In order to add durability to this pliable container and to facilitate its attachment to and removal from the mop handle, the neck (7) is thickened, or preferably beaded, as shown in the drawing.

In using my device a suitable quantity of soap or other detergent is placed in the perforated container (6) and the neck (7), slipped over the bead or projection (5) of

the handle (1). The tassels of mop yarn (2) will now surround and envelop this perforated container. On inserting this mop in water or cleansing liquid, pressure of the end carrying this perforated container against the vessel holding the liquid will cause the pliable material of this container to be pressed inwardly. Upon release of this pressure, the molded rubber of the perforated container (6) will return to its normal position. It will thus be seen that this construction affords a means for circulating the water through this perforated container. In fact, this perforated container of pliable material provides a means for pumping water through the zone holding the soap or other detergent. This soapy water issuing from the perforated container will pass on to the mop yarn (2) and thereby properly condition the mop yarn for scouring and cleansing dishes or similar receptacles.

A very important advantage of my device is the positive circulation of cleansing fluid which may be obtained therewith. Also, by selecting a soap or other detergent of the particular solubility desired, the supply of soap delivered to the mop yarn (2) may be readily controlled.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

I claim as my invention:

1. In a self-soaping dish mop, a handle having at one end a pliable, resilient, perforated container for holding detergent material and for regurgitating liquid through and expelling liquid from said container and mop material secured at said end and adapted to envelop said perforated container.

2. In a self-soaping dish mop, a handle having at one end a resilient perforated container of molded rubber for holding detergent material and mop material secured at said end and adapted to envelop said perforated container, said pliable, resilient, perforated container constituting means for al-

ternately drawing liquid to and forcing liquid from the vicinity of detergent material within the container.

3. In a self-soaping dish mop, a handle having detachably secured at one end a pliable, resilient, perforated container for detergent material and mop material secured

at said end and adapted to envelop said perforated container, said pliable, resilient, perforated container constituting means for effecting positive flow of liquid to and from the vicinity of the detergent material. ¹⁰

In testimony whereof I affix my signature,
HAROLD S. BENNETT.
